UNITED STATES PATENT OFFICE.

THOMAS KELLEY MASSIE, OF HATCHER, WEST VIRGINIA.

BEEHIVE.

1,417,623.

Specification of Letters Patent. Patented May 30, 1922.

Application filed November 25, 1918. Serial No. 264,089.

To all whom it may concern:

Be it known that I, THOMAS KELLEY MASSIE, a citizen of the United States, and a resident of Hatcher, in the county of Mercer and State of West Virginia, have invented certain new and useful Improvements in Beehives, of which the following is a specification.

My invention relates to improvements in beehives, and it consists in the constructions, combinations and arrangements herein described and claimed.

An object of my invention is to provide a beehive which is so arranged that it may either be thoroughly ventilated to keep the interior cool in summer time, or that a dead air space may be formed next to the walls on the inside to serve as insulation and protect the bees in the winter time.

Another object of the invention is to provide a beehive including a bottom-board of such structural design that when it is placed in a level position on a hive-stand or other foundation, will keep the hive perfectly level to the end that perfect combs will be built by the bees; the bottom-board including a sloping floor which tends to drain moisture to the front.

A further object of the invention is to provide a beehive which is constructed and arranged in such a manner that the bees are prevented from gluing the ends of the brood-frames together.

A further object of the invention is to provide a reversible closed-end brood-frame adapted to hang in position and arranged to prevent overturning when stood in position alone.

A further object of the invention is to provide a section holder constructed in such a manner as to prevent the bees from reaching the edges of the sections and covering them with beeswax and propolis, thereby producing clean section boxes when removed from the holders, in readiness for transportation to the market.

Other objects and advantages will appear in the following specification, reference being had to the accompanying drawings in which:

Figure 1 is a perspective view of the beehive arranged for summer use,

Figure 2 is a perspective view of the bottom board,

Figure 3 is a perspective view of one of the inside walls or followers,

Figure 4 is a perspective view of the reversible and removable rear end piece,

Figure 5 is a vertical section of the beehive taken on the line 5—5 of Figure 1 and showing the arrangement for summer use,

Figure 6 is a detail section on the line 6—6 of Figure 5 showing the adjacent follower dropped down inside of the side rail for ventilation in summer use,

Figure 7 is a horizontal section on the line 7—7 of Figure 5,

Figure 8 is a detail section on the line 8—8 of Figure 9 showing the arrangement of the hive for winter use,

Figure 9 is a horizontal section on the line 9—9 of Figure 8,

Figure 10 is a section on the line 10—10 of Figure 5, the arrangement of the hive being for summer use,

Figure 11 is a horizontal section on the line 11—11 of Figure 5,

Figures 12 and 13 are detail sectional views showing how the section boxes are automatically clamped in place in the section holders by means of the end locks and top channels,

Figure 14 is a detail section illustrating a portion of the section holder support,

Figure 15 is an enlarged section showing a portion of the super in Figure 5,

Figure 16 is a detail perspective view of one of the section holders,

Figure 17 is a detail perspective view showing a slight modification in the end lock,

Figure 18 is a perspective view of one of the section separators, and

Figure 19 is a detail perspective view of a portion of one of the improved brood-frames.

In carrying out my invention I provide a beehive made in sections as illustrated in the drawing. The sectional construction of the beehive enables the adding and subtracting of sections as requirements may dictate. In the present instance, the beehive consists of a bottom-board A, one or more brood-chambers B, one or more supers or honey

containers C and a top D. The top D is what is known as a super-cover with an escape in it. Since the present invention is not concerned with the construction of the top 5 D, the construction of the other members of the hive will be described in regular order.

The bottom-board.

The bottom-board A comprises the sloping floor 1 which slopes from the rear to the 10 front of the hive so as to drain the hive of all moisture and assist the bees in removing obstacles which may happen to get into the hive. The sloping floor 1 is fixed between 15 the side rails 2 which in turn are secured on a base board 3. Cleats 4 are fixed on the outside of the side rails 2 and flush with the top surfaces. These cleats provide hand-holds which enable the grasping of the bottom-boards more readily or which enable the entire 20 hive to be lifted when it is desired to move the hive about.

Seats 5 are cut into the side rails 2 near the front and rear extremities. These seats 25 5 receive the followers of the lower brood-chamber when the hive is arranged for summer use. An entrance block 6 is placed across the front of the bottom-board A in the space between the side rails 2 as shown in 30 Figure 2.

A perforated metallic plate 7 spans the space between portions of the entrance block. The perforations of the plate 7 are elongated and are formed in this shape so that only the 35 worker bees may gain entrance to the hive. The entrance block 6 has four functions, namely: it is an entrance contractor, a queen and drone guard, it forms a closure of the space between the side rails and the front, and permits ventilation of the hive.

A removable and reversible rear end piece 8 occupies the space between the side rails 2 beyond the floor 1 at the rear. The rear end piece has a number of bosses between 45 which screen sections 9 are stretched. In the summer time, the rear end piece is turned up in the position illustrated in Figure 2 so that air may enter the hive from the rear through the screen section. For summer use, 50 the front entrance block 6 is removed. In the winter time, the rear end piece is turned over into the position illustrated in Figure 8. In order that the space at the back of the 55 rear end piece 8, grooves 10 are formed in the bosses to receive the rear edge of the floor 1 and form a tight closure.

When the rear end piece 8 is turned over for winter use as just described, the screen 60 sections 9 come adjacent to the rear edge of the floor 1 but the open space between the bosses communicates with the space beneath the floor and not with the interior of the hive, as illustrated in Figure 6. The rear 65 end piece 8 has two functions, namely; it

closes the space under the hive and between the side rails at the rear, when the hive is arranged for winter use, and by reversing the rear end piece, it enables ventilation of the 70 hive from the rear, thereby giving the bees the fresh air without compelling them to seek it at the entrance by "laying out" and idling their time away in extremely hot weather.

The brood chamber.

The brood-chambers B illustrated in the drawing rest one on top of the other and both brood-chambers are supported on the side rails and cleats of the bottom-board A. 80 In this connection it is to be observed that when the bottom-board A is placed on a level foundation, the rest of the beehive structure will be perfectly level in every respect to the important end that perfect combs are built by the bees. A plurality of brood-frames 11 are supported in a hanging position inside of each of the brood-chambers B. For this purpose, a pair of cleats 12 is nailed to the front and rear inside walls of the brood-chamber, upon which the reversible hooks 13 are supported. It is to be observed that the hooks 13 are first bent outwardly at right angles and then back again at 45°. Thus each hook is braced at the supporting points 85 of the brood-frame.

Each hook 13 is pivoted in one of the heads of the brood-frame on the horizontal axis and has a driving point 14 which may be driven into the head either adjacent to the broad top-bar 15 or the narrow bottom-bar 16. Thus it will be observed that by driving the driving point 14 into either of the two positions, the hanging brood-frame 11 is capable of reversal so that either of 105 the bars just mentioned may accordingly come to the top. The narrow-bottom bars 16 best shown in Figure 5, are intended for a specific purpose.

The narrow bottom-bars incite the bees 110 to build their combs down to and over the bar and the arrangement obtained by the construction just recited, reduces the horizontal opening or space between adjacent top and bottom-bars to a considerably less 115 dimension than it has heretofore been able to obtain. These spaces or horizontal openings are made through the solid combs for convenience in handling the different divisions of the hive.

A closure strip 17 is placed across the ends of the brood frame 11 on the top and between the upper and lower brood chambers B as shown in Figure 10. These closure strips have depending pins 18 which 125 enter the space between the heads of the brood-frames and the adjacent walls and keep the closure strips in position. These closure strips connect the inside walls formed by the ends of the brood-frames 11 130

and the followers 19, and prevent the bees from gluing the frames together at the ends. The underlying purpose of the construction described thus far is to provide a perpendicularly connected inside wall all around on the inside of the beehive.

There is one of the followers 19 at each side of the entire body of brood-frames 11. The follower 19 has cleats 20 at the ends, as shown in Figure 3. Springs 21 are secured at one end in the cleats and the springs are intended to press the followers tightly against the adjacent ones of the brood-frames 11 in order to keep all of the brood-frames in tight engagement as clearly shown in Figure 5. The lower end of each cleat 20 is beveled at 22 and the beveled portions terminate in a shoulder 23. A stop 24 is located immediately above the shoulder 23 so that in the case of the lower pair of followers, the stops 24 may rest on the portions of the side rails 2 of the bottom-board A beyond the seats 5 when the hive is arranged for summer use.

25

The super.

The super C consists of a rectangular frame a little more than half the height of the brood-chambers B. Ledges 25 on the front and rear walls of the super and on the inside very near to the bottom, support a plurality of section holders. Each of the section holders include end-bars 26 which are connected at the top and bottom by channels 27 and 28 respectively.

The top channel 27 is simply a U-shaped metallic member which when fitted in place, extends down beyond the edges of the sections 29. The top channel is held in place by end locks 30 which automatically disengage the top channel 27 when the section holder F is pulled out of the super. This action is well illustrated in Figures 12 and 13. The spring-like nature of the end lock 30 of course causes it to move outwardly so that the top channel 27 is disengaged when the section is pulled out as just explained. At the same time, when the section is replaced in the super, the action of the edge of the super on the end lock 30 causes the hook end of the lock to move over the top channel and lock it in place.

A somewhat different structure follows in the case of the lower channel 28. This channel is also substantially U-shape, but the side flanges which protect the edges of the sections 29 are bent up from the body of the channel and then downwardly so as to produce relatively deep aprons 31. These aprons, it will be observed especially in Figure 5, extend down a considerable distance into proximity with the top-bars 15 of the upper brood-frames 11. This arrangement, it will be obvious, provides a guard which keeps the bees from the top rails to a cer-

tain extent and yet leaves a passage between the section holders, permitting the bees to reach the sections. The ends of the aprons 31 are cut away at 32 so as to receive the ledges 25.

It is a very important consideration in the present construction that the section holders are brought closer to the brood-frames than it has heretofore been enabled to obtain. Probably the most important consideration in the present construction of section-holder is, that the edges of the sections 29 are protected throughout, thus enabling the production of absolutely clean sections in readiness for the market. It often occurs that where the edges of the sections are not protected, much time must be spent in scraping the edges in order to give them the necessary clean appearance to make the sections salable. Separators 33 are located between the various section holders. These separators are of an ordinary construction and include the slats and end pieces that hold the slats together, as shown in Figure 18. The upper portions of the end pieces are cut away at 34 to accommodate the flanges of the upper and lower channel members 27 and 28.

In order to sustain the weight of the honey in the sections and to prevent the bottom channel 28 from sagging, hooks 35 which reach from the upper to the lower channel are provided. One of the hooks will ordinarily be sufficient to support the lower channel, but obviously one hook on each side may be used to better advantage as illustrated in Figure 15. These hooks are loosely fitted in the bottom channel and the lower hooked end is simply slipped into a suitable hole in the flange of the top channel. With reference to the end locks previously described, this construction is capable of modification as illustrated in Figure 17. Here the end lock 30^a is integral with the top channel 27 and simply slips over a stud 36 which holds the top channel in place.

Arrangement for summer use.

When the hive is thus arranged, the various parts appear with respect to the front and back of the hive as illustrated in Figures 1, 5, 6 and 7. Here it will be observed at once that the followers 19 or the inside walls of the brood-chambers M are dropped down inside of the side rails 2. This feature of coacting or cooperative membering of hive-units is a new and novel one never before used in hive construction. At this time, the stops 24 rest on the side rails beyond the seats 5 as clearly shown in Figure 5. By reason of the sloping position of the bottom 1 the rear lower edge of the bottom side walls contact the bottom, but since the side walls rest on the side rails as just explained, 130

there is an increasing air space toward the front as clearly shown in Figure 6. The rear end gate is reversed so that there is air communication with the space E completely around the hive. Air may enter at the front and rear and pass up the space E on all sides. This provides continuous ventilation which keeps the inside of the hive cool and avoids the necessity on the part of the bees of seeking the entrance of the hive in order to obtain fresh and cool air. This has the important advantage of preventing the bees from "laying out" and idling their time away. In winter time a closed telescope cover is put on top of the super-cover C. In this telescope cover, which however is not illustrated in the drawings, a cushion of absorbent material is fastened so that it does not become an extra loose part to be handled. This cushion prevents the radiation of the bee-heat. Even after the side walls 19 are dropped down inside of the side rails 2 as just explained, they remain connected intermittently as clearly shown in Figure 5. The space E thus remains continuous until the proximity of the upper edge of the top brood-chamber is reached. The closure strips 17 prevent the bees from reaching the ends of the brood-frames and gluing them together.

Arrangement for winter use.

The beehive is now turned around 90° with respect to the bottom-board B. Where the brood-frames 11 were formerly parallel with the side rails 2, they are now arranged transversely thereof as shown in Figures 8 and 9, thus forming a windbreak of the first or outside comb for winter protection of the bees. The rear end piece is turned over with the wire cloth side down, since a more tight closure between the front follower 19 and the entrance block 6 may thus be obtained.

The followers or inside walls 19 in the lower brood-chamber B are set into the seats 5 whereupon the lower edges of the walls come very close to the adjacent edges of the members 6 and 8. The space E is completely closed at the back and is so nearly completely closed at the front that but little air can enter the space from this side. When the closed top just spoken of is placed on top of the upper brood-chamber, the air space E will be practically dead and offer an effective insulation that prevents the heat from the inside of the hive from escaping through the walls.

60

The brood-frame 11

embodies a novel construction as illustrated in Figure 19. The top rail 15 hereinbefore generally referred to is made in two parts; 65 the fixed part 15 and the movable part 15^a.

The part 15^a is separable to enable the ready placing of the comb foundation in the top rail. The member 15^a is secured in place by means of double-pointed tacks and the two parts are clamped together at the middle by a wire clamp of any suitable type. Modifications and changes in the manner of using the double-pointed tacks or staples may be made without departing from the spirit of the invention or the scope of the claims. 75

Ordinarily the comb foundation is put in place by means of a wedge which is driven against the comb foundation in saw kerfs in the under surface of the top rail. This wedge is susceptible to shrinkage and thereby permits the loosening of the comb foundation. The construction just described and illustrated in Figure 19 positively prevents the loosening of the comb foundation since it is held in place by the clamping action of the device just described. 80

While the construction and arrangement of the beehive as herein described and claimed is that of a generally preferred form, obviously modifications and changes 90 may be made without departing from the spirit of the invention or the scope of the claims.

I claim:—

1. A beehive comprising a relatively fixed bottom-board, a sectional body including a brood-chamber and super arranged to be placed on the bottom-board in either of two positions, and means located inside of the brood-chamber arranged to coat with a portion of the bottom-board to provide a dead air space when the body rests in one position on the bottom-board, and to enable the ventilation of the hive when the body is placed in the other position on the bottom-board. 95 100 105

2. The combination in a beehive, of a bottom-board, side rails on the bottom-board, a brood-chamber containing a plurality of hanging brood-frames and arranged to be set on the bottom-board in either of two 110 positions with the brood-frames parallel to or disposed transversely to the side rails, and means at the sides of the plurality of brood-frames adapted to occupy a position in spaced relationship to the side rails when the brood-frames are parallel thereto and provide a ventilating space. 115

3. The combination in a beehive, of a bottom-board including side rails, a brood-chamber arranged to be set on the bottom-board in either of two positions, a row of brood-frames supported in the brood-chamber, said brood-frames having heads engaging one another and providing a space at the front and rear, followers at the sides of the row of brood-frames in spaced relationship with the adjacent walls of the brood-chamber and arranged to be dropped inside of the side rails when the brood-chamber is placed on the bottom-board with the brood- 120 125 130

- frames parallel to the side rails, to provide a space between said followers and side rails for ventilation, a screened rear end piece connecting the side rails, and admitting air 5 to the space at the rear, and an entrance block connecting the side rails at the front admitting air to the space at the front.
4. The combination in a beehive, of a bottom-board including side rails, a brood-chamber arranged to be set on the bottom-board in either of two positions, a row of brood-frames supported in the brood-chamber, said brood-frames having heads engaging one another and providing a space at the 10 front and rear, followers at the sides of the row of brood-frames in spaced relationship with the adjacent walls of the brood-chamber and arranged to be dropped inside of the side rails when the brood-chamber is placed 15 on the bottom-board with the brood-frames parallel to the side rails, to provide a space between said followers and side rails for ventilation, a screened rear end piece connecting the side rails and admitting air to 20 the space at the rear, and an entrance block connecting the side rails at the front admitting air to the space at the front, said rear end piece being reversible to enable the closure of the space between the followers 25 and adjacent walls of the brood-chamber when the brood-chamber is placed on the bottom-board with the brood-frames arranged transversely with respect to the side rails and the followers in contact with said 30 rear end piece and entrance block.
5. In a beehive, a bottom-board including side rails, cleats attached to the side rails enabling the grasping of the bottom-board and providing a broader brood-chamber supporting surface, a floor fixed between the side rails and inclined from the rear to the front to drain the hive of moisture, and a reversible rear end piece connecting the side rails at the back and having slots arranged 35 to fit over the rear edge of the floor when the rear end piece occupies one position.
6. In a beehive, a bottom-board including side rails having notches providing seats near the front and rear of the hive, a sloping 40 floor fixed between the side rails, an entrance block arranged to connect the side rails at the front, a reversible rear end piece arranged to connect the side rails at the rear and having grooves fitting over the rear edge 45 of the floor, a brood-chamber arranged to be set upon the side rails and the rear end piece and front entrance block, a plurality of hanging brood frames in the brood-chamber having heads forming a pair of walls in 50 spaced relationship to the adjacent walls of the brood-chamber, and inside walls closing the sides of the brood-frames and adapted to occupy the seats in the side rails when the brood frames are disposed transversely 55 of the side rails.
7. The combination in a beehive, of side rails having notches providing seats, a brood-frame arranged to be set on the side rails and having a pair of followers forming inside walls, cleats strengthening the vertical ends of the followers and having beveled portions at the bottom, said followers being arranged to be dropped down inside of the side rails to provide spaces for ventilation when the followers are arranged parallel to 70 the side rails, and lugs carried by the followers adjacent to the beveled portion arranged to reach across said cleats and rest on the side rails.
8. In a beehive, a pair of brood-chambers 80 arranged to be set one upon the other, a plurality of brood-frames of a lesser height than said brood-chambers equal to an exact bee-space, means enabling the hanging of the brood-frames in said chambers, and closure strips arranged to be laid transversely of the brood-frames between the pair of chambers to connect the brood-frames and prevent the bees from gluing the ends.
9. In a beehive, a brood-chamber having 90 supporting cleats on opposite walls and near the top, a brood-frame arranged to be supported on said cleats and including heads, a hook including a shank pivoted in the middle of each of the heads, and a driving point formed on the shank beyond the hook enabling the disposition of the hook in either of two positions and the consequent reversal of the brood-frames.
10. The combination in a beehive, of a 100 brood-chamber containing a plurality of hanging brood-frames each having a top-bar, a super resting on the brood-chamber and having ledges close to the bottom edge, and section holding means including a bottom channel having flanges extending close to the adjacent top-bars of the brood-frame.
11. In a beehive, a super having a pair of supporting ledges, a plurality of section holders arranged to rest on the ledges, and means included in the section holders enabling the simultaneous release of the sections with the withdrawal of said section holders from the super.
12. In a beehive, a super, a pair of ledges, 115 section holders including end bars, a bottom channel connecting the end bars including relatively deep flanges and a U-shaped portion, said flanges having cut-away ends to rest on the ledges, a removable top channel, the 120 flanges of both channels being adapted to cover portions of the sections held in the holder to keep the edges clean, means providing a support for the bottom channel from the top channel, and end locks carried 125 by the end bars engaging the top channel when the section holder is forced into the super.
13. In a beehive, a super having supporting ledges, a plurality of section holders rest- 130

ing on the supporting ledges and including top and bottom channels arranged to protect the edges of honey sections, and separators between the section holders including 5 end cleats having cut-away portions to accommodate the flanges of said top and bottom channels.

14. In a beehive, a brood-frame consisting of end members, a top rail portion fixed in 10 place between said end members, a separable top rail portion arranged to be clamped against said fixed rail portion to hold a comb foundation in position, and securing means for holding the two rail portions together.

15. 15. A beehive, including a bottom board having side rails with end notches, and a brood chamber with pendent brood frames having 20 side closure partitions occupying the notches inside of said rails to provide air 20 passages when the brood chamber is in one position on the side rails.

16. A beehive, including a bottom board having side rails with end notches, a brood chamber with pendent brood frames having 25 side closure partitions occupying the notches inside of said rails to provide air passages when the brood chamber is in one position on the side rails, and closure strips extending 30 between the side rails, supporting said partitions to close the air passages and provide a dead air space, when the brood chamber is turned ninety degrees in respect to the bottom board.

17. A beehive, including a bottom board 35 with side rails and end closure strips, and a plurality of brood chambers, each with a pendent brood frame having contacting

heads spaced from adjacent chamber walls, and side closure partitions, those of the lowermost brood chamber resting on the closure strips and engaging the partitions of the chamber above, to make continuous walls and a surrounding dead air space. 40

18. A beehive, comprising a brood chamber, and a plurality of brood frames with 45 mutually contacting heads spacedly supported from adjacent chamber walls, having followers spaced from the other chamber walls and closing the brood frame sides, the foregoing providing a continuous inside wall 50 with a surrounding air space.

19. A beehive, comprising a brood chamber, a plurality of brood frames with 55 mutually contacting heads spacedly supported from adjacent chamber walls, having followers spaced from the other chamber walls and closing the brood frame sides, the foregoing providing a continuous inside wall with a surrounding air space, and a bottom board on which the brood chamber is set, 60 arranged to permit the followers to be dropped down and break the continuity of said inside wall and the completeness of said air space for ventilation.

20. A beehive, comprising a plurality of 65 brood frames with mutually contacting heads forming complete end walls, with followers closing the open sides, all being glued together by the bees in the operation of the 70 hive; and a brood chamber in which the foregoing structure is supported, capable of being lifted off without disturbing said structure or the bees contained therein.

THOMAS KELLEY MASSIE.
